UNITED STATES PATENT OFFICE.

JOHN H. LOVE, OF PAWHUSKA, AND KIT C. LOVE, OF MUSKOGEE, OKLAHOMA.

DESIGN FOR A BOTTLE.

Application filed June 16, 1928. Serial No. 27,171. Term of patent 7 years.

To all whom it may concern:

Be it known that we, JOHN H. LOVE and KIT C. LOVE, citizens of the United States, and residing, respectively, at 551 Tinker Avenue, city of Pawhuska, in the county of Osage and State of Oklahoma, and at 561 North Third St., city of Muskogee, in the county of Muskogee and State of Oklahoma, have invented a new, original, and ornamental Design for Bottles, of which the following is a specification, reference being had to the accompanying drawing, forming part thereof.

The figure is a side view in elevation of a bottle, showing our new design.

We claim:

The ornamental design for a bottle, as shown.

JOHN H. LOVE.
